ARTICLE ASSORTING APPARATUS

Richard A. Spraker, Fairfield, Conn., assignor to
 Remington Arms Company, Inc., Bridgeport,
 Conn., a corporation of Delaware

Application March 29, 1944, Serial No. 528,606

6 Claims. (Cl. 209—72)

1

The present invention relates to article sorting apparatus, and particularly to a feeding apparatus adapted to sort and feed articles from a bulk hopper in side by side relation and in correct endwise orientation to a feed magazine or the like, which in turn feeds the articles in succession to an automatic processing machine. The invention is predicated upon the sorting and feeding of articles which are essentially of elongated form and substantially heavier at one end than the other, such articles being, for instance, cartridge case components in a given stage of their manufacture. Such components are in the form of a cylindrical tube open at one end and provided at its other end with a heavy head forming closure, and whereby the balancing point of the component is at one side of the medial point and toward the heavier head end. In certain processing operations the components are fed into a magazine in side by side relation, as distinguished from end to end relation, and with the head ends all disposed in the same direction. It is an object of the present invention to provide an apparatus especially adapted for the effectual feed of elongated off-center-balanced articles in side by side relation and in uniform endwise orientation, and wherein it is proposed to employ the force of gravity in cooperation with the apparatus and the articles to accomplish this end.

It is a further object to provide a mechanism of relatively simple construction, which may be continuously operated to feed the articles at a speed approximating the speed of the processing machine, and which is free from complicated working parts, making it relatively easy to maintain in working order.

A further object is to provide automatic means actuated by the articles being fed to stop the feed of the articles to the magazine as the latter becomes filled to a predetermined height, thus preventing jamming at the point of entry to the magazine.

With the above and other objects in view an embodiment of the invention is shown in the accompanying drawing, and this embodiment will be hereinafter more fully described with reference thereto, and the invention will be finally pointed out in the claims.

In the drawing—

Fig. 1 is a front elevation of the article sorting device, according to the illustrated exemplary embodiment of the invention.

Fig. 2 is a vertical sectional view, taken along the line 2—2 of Fig. 1, and partially broken away.

Fig. 3 is a top plan view showing the upper end

2

of the feed magazine and the automatic trip gate mechanism, the main feed hopper for cooperation therewith being removed.

Fig. 4 is a vertical sectional view of the lower portion of the device, taken along the line 4—4 of Fig. 2, and showing the trip gate mechanism in its operative or open position.

Fig. 5 is a similar view showing the trip gate mechanism in its inoperative or closed position. 10 Similar reference characters indicate corresponding parts throughout the several figures of the drawing.

Referring to the drawing, the article sorting machine, according to the illustrated exemplary 15 embodiment of the invention shown therein, comprises a stationary hopper, indicated generally as 10, of cylindrical form disposed in upright position with its central axis horizontally disposed, being provided in its vertical front wall 11 with 20 an article receiving opening 12 having secured in the lower portion a forwardly projecting bin 13. The lower edge of the bin is disposed in concentric relation substantially inwardly of the outer periphery of the wall 11, so that the wall is provided 25 with a continuous flat circumferential marginal portion disposed in a vertical plane.

The hopper constitutes a housing for a rotatable paddle wheel, presently to be more fully described, and for this purpose is provided with a cylindrical side wall 14 open at its rearward side, the 30 hopper being provided at its upper side with an inwardly projecting dome portion 15 adapted to provide a clearance space about the upper portion of the paddle wheel, the front wall of this dome portion being continuously formed with the front wall 11 and the rear wall being provided 35 with an arcuate lower edge 16 forming a circumferential continuation of the inner cylindrical surface of the side wall 14 to provide therewith a circular opening for receiving the paddle wheel.

Upon the inner side of the front wall 11 there 40 is secured a rearwardly projecting baffle wall 17 inwardly spaced from the outer wall 14 and starting at a point at one side slightly below the horizontal diametric plane of the hopper and extending therefrom in the direction of rotation of the paddle wheel to a terminal point at the other side and in the lower region of the hopper. The end portion of the baffle adjacent its terminal point 45 is preferably curved inwardly, as at 18, out of concentric relation. The baffle is of approximately half width from its starting point at one side to a point at the other side a short distance above the horizontal diametric plane of the hopper, and from which latter point it is of full width to its

terminal end, the half width portion traversing the clearance space provided across the dome 15.

The articles to be sorted are essentially elongated and are essentially heavier at one end than the other, being shown for example as tubular cartridge case components A closed at their head end, so that the balance point of the component is at one side of its medial point and toward the head end. The half width portion of the baffle is such that when the components are being fed thereon by the paddle wheel, as will presently more fully appear, any component having its head end disposed forwardly upon the half width portion will remain thereon, due to the fact that its balance point is forwardly of the edge of the half width portion. On the other hand, any component which is wrong end to, that is with its head end disposed rearwardly, will be overbalanced and will tip over the edge of the half width portion as the paddle wheel traverses the clearance gap provided by the dome 15, dropping by gravity back into the lower region of the hopper.

The paddle wheel comprises a circular disk 19, rotatably engaged within the circular opening at the rear side of the hopper, and provided with a circular series of forwardly projecting radially disposed paddle vanes 20, slightly less in height than the width in the channel space provided between the baffle and the hopper wall, so that as the wheel is rotated the paddle vanes move through this channel space. The disk 19 is provided with a central hub 21 secured to a shaft 22 which is driven by suitable means to rotate the disk slowly within the hopper.

The components are placed in the bulk hopper and bin in quantity so that they are promiscuously disposed therein. As the paddle wheel rotates certain of the components will be engaged by gravity and agitation in the pocket spaces between the vanes, and as they are carried through the lower region of the hopper into relation with the starting end of the baffle those components fully seated therein will be carried upwardly into the channel space, while those not fully seated will be deflected back into the hopper. Those components carried by the paddle wheel into the channel space will be disposed with their head ends either forwardly or rearwardly, and as the paddle wheel traverses the clearance gap provided by the dome 15 those components which have their head ends rearwardly will drop off the baffle, while those with their head forwardly will be carried beyond the gap and into relation with the full width retaining portion of the baffle. The full width portion provides a cover for the paddle vanes as they move into the lower part of the hopper, preventing interference of the components in the hopper with those carried in the paddle wheel. The spacing of the terminal end 18 of the hopper from the paddle wheel vanes is substantially less than the diameter of the components so that the components in the hopper cannot enter beneath this terminal end.

In opposed relation to the terminal end portion 18 of the baffle there is provided an outlet opening 23, corresponding substantially in width to the width of the spaces between the paddle wheel vanes, the lower surface of the cylindrical wall 14 and the front wall 11 being arcuately recessed, as at 24, for the purpose of cooperation therewith of the trip gate presently to be more fully described. In line with the opening 23 there is provided a gravity feed magazine or chute 25, of rectangular cross section, into which the components drop by gravity through the opening 23

in side by side relation with their head ends uniformly oriented forwardly. A bracket 26 is secured to the magazine 25, and pivotally supports a lever arm 27 upon the upper end of which there is secured a gate member 28, in the form of a plate curved in concentric relation to the pivotal axis of the lever 27 with its upper convex surface having bearing in the arcuate recess 24. A rectangular opening 29 is provided in the gate somewhat longer than the external long dimension of the magazine and slightly greater in width than the internal short dimension of the magazine, so that in the open position of the gate the inner edge of the opening rests upon the upper end of one wall of the magazine while the outer edge abuts the outer surface of the opposed wall of the magazine, the opposed wall being projected upwardly above the other three walls, as at 30, to provide such abutment. These other three walls are preferably convexly formed at their upper ends to engage and conform to the concave under side of the gate. In the closed position of the gate, as shown in Fig. 5, the inner wall of the opening abuts the inner surface of the abutment portion 30.

The lever 27 may be provided with a forked trip finger 31 extending downwardly in inclined relation through openings 32 in the wall of the magazine, and normally extending across the magazine to provide a support therein for the components. An adjustable counter-weight 33 is carried upon a threaded arm 34 secured to the lever 27, and normally maintains the gate 28 in open position and the trip finger in supporting relation within the magazine, being suitably adjusted to balance the weight of a predetermined number of components.

In operation the components are successively fed from the paddle wheel into the magazine until the predetermined number have accumulated upon the trip finger to overbalance the counter-weight, whereupon the trip finger moves outwardly to release these components and at the same time close the gate 28, so that feed of the components into the magazine is interrupted. If there is normal feed of the components from the magazine to the processing machine the components released by the trip finger will drop to a point clear of the trip finger, so that automatically the latter will return immediately to operative position, under action of the counter-weight, and the gate 28 will open. However, in case of interruption in the feed of the components from the magazine, so that they begin to build up in the magazine, the components released by the trip finger will not be carried below the trip finger but will be disposed in line with the end surfaces 35—35 thereof, thus preventing the trip finger from moving inwardly under the action of the counterweight, as shown in Fig. 5, the gate 28 remaining closed. This condition will continue until the height of the components in the magazine drops below the trip finger to release it, whereupon the gate opens and the normal feed continues. When the gate 28 is closed the components in the paddle wheel pockets remain therein and are carried around with the paddle wheel until they are finally fed into the magazine.

The form of the invention illustrated in the drawing and described herein is typical and illustrative only, and it is evident that the invention is capable of embodiments in other forms, all falling within the scope of the appended claims, which are to be broadly construed.

What is claimed is:

1. In an apparatus for sorting and feeding elongated articles heavier at one end than the other, a bulk hopper having a circumferential outer wall extending about the bottom and sides thereof, there being a clearance gap in said wall in the upper region of the hopper, a circumferential baffle wall of varied width fixed within said hopper in inwardly spaced concentric relation to said circumferential outer wall to form an annular channel therebetween and extending upwardly from a point at one side of the hopper below and contiguous to the diametric horizontal plane of the hopper across said clearance gap and downwardly to a point at the other side below said clearance gap, a rotatable paddle wheel comprising a substantially flat thin disk having a circular series of spaced paddle vanes on one face thereof arranged to engage and move in the annular channel between said outer wall and said baffle wall, the portion of said baffle wall traversing said clearance gap being of substantially half width and extending approximately half-way across said hopper, whereby articles carried upwardly by said paddle wheel and disposed with their heavy end on said half width portion will remain thereon as the paddle wheel continues in its downward movement, while reversely disposed articles will tilt and drop therefrom, said hopper having an outlet opening at a point opposed to said baffle wall through which drop the articles carried downwardly by said paddle wheel.

2. In an apparatus for sorting and feeding elongated articles heavier at one end than the other, a bulk hopper having a circumferential outer wall extending about the bottom and sides thereof, there being a clearance gap in said wall in the upper region of the hopper, a circumferential baffle wall of varied width fixed within said hopper in inwardly spaced concentric relation to said circumferential outer wall to form an annular channel therebetween and extending upwardly from a point at one side of the hopper across said clearance gap and downwardly to a point at the other side in the lower region of said hopper, a rotatable paddle wheel comprising a substantially flat thin disk having a circular series of spaced paddle vanes on one face thereof arranged to engage and move in the annular channel between said outer wall and said baffle wall, the portion of said baffle wall traversing said clearance gap being of substantially half width and extending approximately half-way across said hopper, whereby articles carried upwardly by said paddle wheel and disposed with their heavy end on said half width portion will remain thereon as the paddle wheel continues in its downward movement, while reversely disposed articles will tilt and drop therefrom into the lower region of said hopper, said baffle wall being of full width from a point above the diametric horizontal plane of the hopper to its lower terminal end to form a cover for said paddle vanes thereby preventing interference of the articles in the hopper with the oriented articles in the paddle wheel, said hopper having an outlet opening at a point in its lower region opposed to said baffle wall through which drop the articles carried downwardly by said paddle wheel.

3. In an apparatus for feeding elongated articles in side by side relation, a bulk hopper, an article feeding paddle wheel within said hopper having a circular series of spaced paddle vanes for individually feeding said articles in successive side by side relation, said hopper having an

outlet opening at a point in its lower region through which individually drop the articles carried by said paddle wheel, a feed magazine in communication with said opening for receiving the articles in side by side relation, a movable gate for said outlet opening arranged when closed to support articles in said paddle wheel, and actuating means for opening and closing said gate movably disposed in said magazine in the path of the articles passing therethrough to support them, a predetermined number of such articles adapted by their weight to move said actuating means in gate closing direction to allow passage of said articles, said actuating means adapted to be prevented from movement within said magazine in gate opening direction by an arrested article disposed in its return path.

4. In an apparatus for feeding elongated articles in side by side relation, a bulk hopper, an article feeding paddle wheel within said hopper having a circular series of spaced paddle vanes for individually feeding said articles in successive side by side relation, said hopper having an outlet opening at a point in its lower region through which individually drop the articles carried by said paddle wheel, a feed magazine in communication with said opening for receiving the articles in side by side relation, a movable gate for said outlet opening arranged when closed to support articles in said paddle wheel, and a counterweighted trip lever for opening and closing said gate having a trip portion movably disposed in said magazine in the path of the articles passing therethrough to support them, a predetermined number of such articles adapted by their weight to move said lever in gate closing direction to allow passage of said articles, said lever adapted to be prevented from return movement within said magazine in gate opening direction by an arrested article disposed in its return path.

5. In an apparatus for sorting and feeding elongated articles heavier at one end than the other, a bulk hopper having a circumferential outer wall extending about the bottom and sides thereof, there being a clearance gap in said wall in the upper region of the hopper, a circumferential baffle wall fixed within said hopper in inwardly spaced relation to said circumferential outer wall extending upwardly from a point at one side of the hopper across said clearance gap and downwardly to a point at the other side in the lower region of said hopper, a rotatable paddle wheel having a circular series of spaced paddle vanes engaged and movable in the annular channel between said outer wall and said baffle wall, the portion of said baffle wall traversing said clearance space being of substantially half width and extending approximately half-way across said hopper, whereby articles carried upwardly by said paddle wheel and disposed with their heavy end on said half width portion will remain thereon as the paddle wheel continues in its downward movement, while reversely disposed articles will tilt and drop therefrom into the lower region of said hopper, said baffle wall having an outlet opening at a point in its lower region opposed to said baffle wall through which individually drop the articles carried downwardly by said paddle wheel, a feed magazine in communication with said opening for receiving the articles in side by side relation, a movable gate for said outlet opening arranged when closed to support articles in said paddle wheel, and actuating means for opening and closing said gate movably disposed

in said magazine in the path of the articles passing therethrough to support them, a predetermined number of such articles adapted by their weight to move said actuating means in gate closing direction to allow passage of said articles, said actuating means adapted to be prevented from return movement within said magazine in gate opening direction by an arrested article disposed in its return path.

6. Apparatus for the delivery in a desired orientation of elongated articles having a heavy end comprising a rotatable plate mounted on a horizontal axis; article supporting and transferring vanes projecting from one face of said plate in substantial parallelism with the axis thereof; a substantially cylindrical stationary drum housing comprising a fragmentary end plate disposed in substantial parallelism with said rotatable plate and spaced therefrom by a distance slightly greater than the length of the articles to be ori-

10 5 15 20

mented and a side wall which is generally cylindrical and coaxial with the axis of said rotatable plate and comprises an outward enlargement at the upper portion thereof; hopper means for introducing articles to be oriented into said drum housing; and a stationary arcuate article separating baffle coaxial with said rotatable plate secured to said stationary housing and forming with the side wall thereof a channel for the passage of said vanes and the elongated articles transferred thereon, said baffle being cut away in the region opposite the enlargement in the top of said side wall to afford a support for substantially one-half the length of the elongated articles being transferred, and a portion of the baffle in the direction of article transfer from said enlargement being extended to afford a separation of oriented articles in transit from articles being supplied by said hopper means.

RICHARD A. SPRAKER.
